UNITED STATES PATENT OFFICE.

DONALD S. BARROWS, OF ROCHESTER, NEW YORK, ASSIGNOR TO THE SYMINGTON COMPANY, OF NEW YORK, N. Y., A CORPORATION OF MARYLAND.

DRAFT RIGGING.

Application filed November 14, 1925. Serial No. 69,094.

This invention relates to railway draft rigging and more particularly to a construction in which a direct swiveling motion is permitted between a horizontal yoke and a 5 cooperating coupler.

The principal object of my invention, generally considered, is the provision of a draft rigging construction preferably employing only one key which serves for supporting the 10 forward portion of the yoke and transmitting draft forces to the car sills, a direct swiveling connection being provided between the butt of the coupler and the forward portion of the yoke, the rear end of said 15 yoke being slidably received in a pocket provided in a cooperating backstop.

Another object of my invention is the provision of a draft rigging construction involving a horizontal yoke with an integral, 20 swivel block portion at the forward end thereof, said swivel block portion serving for directly engaging, at its rear face, a front follower member and provided with a forwardly opening pocketed portion for receiving the butt of the associated coupler and articulated with respect thereto.

A further object of my invention is the provision of a draft rigging mechanism involving a yoke of the horizontal type associated with a backstop provided with a forwardly opening pocket for receiving the 30 rear end of the yoke and allowing sliding motion therein, upright abutments being provided adjacent said pocketed end of the 35 backstop for transmitting buffing forces from a rear follower member, embraced by the yoke, to the center sills of the car.

A still further object of my invention is the provision of a draft rigging arrangement involving the employment of a closed yoke of the horizontal type, one draft key 40 only being preferably employed for supporting said draft rigging adjacent the forward portion of the yoke, the rear portion of said yoke being supported by a hollow backstop member and the forward portion of said yoke being connected to the butt of a cooperating coupler by means of an upright pin allowing swiveling motion therebetween.

Other advantages and objects of the invention relating to the particular arrangement and combination of the various parts will become apparent as the description proceeds.

Referring to the drawings illustrating my invention, the scope whereof is defined by the appended claims:

Figure 1 is a plan view, partly in horizontal section, illustrating a draft rigging 60 arranged between the center sills of a car and embodying features of my invention.

Figure 2 is a vertical central longitudinal section of the embodiment of my invention illustrated in Figure 1.

Referring to the drawings in detail, like parts being designated by like reference characters, the center sills of a car are indicated fragmentarily at 1, said sills being illustrated as of the channel type with upright web portions 2 and outwardly extending 70 upper and lower flanges 3.

Connected to the webs of the center sills are cheek plates 4 which, in the embodiment disclosed, are each provided with a single slot 5 therethrough, said slots being defined by flange portions 6 bordering the same and the inwardly extending sections 7 of which extend into and closely fit within corresponding slotted portions 8 of the center sill 80 webs 2. The cheek plates 4 are shown connected on the outside faces of the webs 2 of the center sills thereby allowing a slightly greater space between the same for the reception of the associated draft gear but, if desired, the same may be applied on the inside faces of said sills.

Supported on the flanges 6 of the cheek plates 4 and extending through the slots 5 therein is a key 9 which functions to transmit draft forces from follower 10 which is supported directly thereon by the key extending through a registering slot therein. A yoke 11 is similarly supported upon the draft key 9, by said draft key extending 90 through registering slots 12 in the arms of said yoke preferably adjacent the forward end thereof. In the present embodiment of my invention, the yoke is of the horizontal type and is preferably formed by casting, the rear end of said yoke being U-shaped 100 in accordance with the usual practice. Said U-shaped portion supports a rear follower member 13 in the usual manner and between the follower members 10 and 13, cushioning mechanism 14 of any desired form is provided, as indicated diagrammatically by dot and dash lines. The rear end of the yoke 11 is supported by backstop casting 15 by 105 extending into a pocketed portion 16 there- 110

of and being supported on upstanding web 17, extending transversely, and longitudinally extending webs 18 for rigidifying said casting and bracing the web 17 with respect to the floor or lower web 19 of the casting.

The backstop casting 15 is preferably provided with side walls 20 extending longitudinally along the webs 2 of the center sills and rigidly connected thereto by means of rivets 21. Said walls are braced together and connected to the longitudinally extending web or flange portions 18 by means of a transversely extending web 22, the central portion of said web being apertured to form a thimble 23 for the reception of the usual king pin. The side walls of the casting are also joined together by substantially horizontal web 24 defining the upper limit of the pocket 16 and provided at its forward edge with an upstanding flange or web 25. The webs or flanges 17 and 25 serve as abutments for the rear follower 13 thereby transmitting buffing forces therefrom to the underframe of the car. The upright web or flange portion 25 is, therefore, preferably reinforced by longitudinally extending web or gusset portions 26 which preferably taper rearwardly and gradually merge into the web 24. The sides of the web 25 are preferably extended diagonally outwardly and rearwardly to join with the side walls 20 of the casting and a similar construction is provided with respect to the web or flange 17.

Although the U-shaped portion of the yoke 11 may be constructed in any desired manner, yet for adequate strength, it is preferably of I or H section adjacent its central longitudinal section and the forwardly extending arms therefrom preferably increase in width gradually toward the forward ends thereof to thereby compensate for the slots 12 therein. The forward ends of said arms are preferably joined by an integral bridge or diaphragm portion 27, the rear face of which directly engages the front follower 10 and the forward portion of which is pocketed for receiving the butt of an associated coupler 28. A pin 29 serves for pivotally connecting said coupler and yoke and allowing a desired amount of angling therebetween.

In the present embodiment of my invention, the diaphragm portion connecting the forward ends of the arms of the yoke is formed with forwardly extending webs or flanges 30, 31 and 32 which provide pockets therebetween for receiving the rearwardly extending webs or flanges 33 and 34 of the coupler 28. All of said webs or flanges 30, 31, 32, 33 and 34 are curved coaxially with respect to the pin 29 along their free edges and the pockets between said flanges are likewise formed with complementary curved bearings for said flanges, likewise curved coaxially with respect to the pivotal pin 29,

thereby increasing the bearing area between said coupler and yoke for adequately transmitting buffing forces therebetween. In addition to the pockets provided between the flanges for receiving the corresponding flanges of the cooperating members, flanges or webs 35 and 36 positioned respectively on the upper and lower surfaces of the coupler butt are preferably provided for engaging the forwardly extending flanges 30 and 32 from the yoke. Said flanges 35 and 36 are also preferably curved coaxially with respect to the pin 29 and the ends thereof are preferably braced by diagonally extending wing or gusset portions 37, the ends of which merge into the respective faces of the coupler.

For securing the pin 29 in position and preventing undesired removal thereof, any usual form of locking means therefor may be provided. In the present embodiment, I have shown perforated lug portions 38 on the upper surface of the flange 30 and corresponding lug portions 39 on the lower surface of the flange 32, said portions lying on opposite sides of the pivot pin 29, which extends through registering apertures in the flanges 30, 31, 32, 33 and 34, and are adapted for receiving locking bars or cotters 40 and 41 respectively. After insertion of the members 40 and 41 through the apertures in lugs 38 and 39 respectively, the ends, or straight end, of each of said locking members may be bent, as illustrated particularly in Figure 2, for securely holding them in place for locking the pivot pin 29 in position. Preferably prior to insertion of the members 40 and 41 in place, one end is bent to position to serve as a head thereby necessitating the bending of only the other end for locking each member in place.

Although I have shown a swiveling arrangement between coupler and yoke without the employment of any key for directly supporting the coupler, the only key used being for directly supporting the forward portion of the yoke at the rear of the swivel block portion or diaphragm 27, it is obvious that I do not wish to be restricted to such a construction as, if desired, I may employ a swiveling arrangement such as disclosed in my co-pending application, Serial No. 4,443, filed January 24, 1925. That is, the inner flange 31 on the yoke may be formed considerably thicker and bifurcated and the flanges 33 and 34 on the coupler spaced further apart so that a slot may be provided through coupler and yoke for the reception of a supporting draft key, as shown in said co-pending application.

By virtue of the aforescribed construction, I have provided an economical draft rigging in which angling is permitted between coupler and yoke and in which expense may be saved and economy effected in weight

by eliminating a front key and providing single slotted cheek plates as well as avoiding the necessity of a separate swivel butt for the coupler.

5 Having now described my invention, what I claim is:

1. In a draft rigging, in combination with the center sills of a car, a horizontal yoke positioned between said sills, and a coupler 10 with its butt portion pocketed in and directly swiveled with respect to said yoke.

2. In a draft rigging, in combination with the center sills of a car, a horizontal yoke positioned between said sills and formed 15 with a forwardly opening pocketed portion at its front end, a coupler with its butt end extending into said pocketed portion and an upright pin extending through said end and the adjacent walls of the yoke for connecting the members together and permitting swiveling motion therebetween.

3. In a draft rigging, in combination with the center sills of a car, a horizontal yoke positioned between said sills and formed 25 with a rear U-shaped portion and forwardly extending arms, the forward ends of said arms being integrally united to a forwardly opening swivel block, and a coupler extending into and articulated with respect to said 30 block.

4. In a draft rigging, in combination with the center sills of a car, a horizontal yoke positioned between said sills and formed with a rear U-shaped portion and forwardly 35 extending arms, the forward portions of said arms being slotted and the ends continued forwardly of said slotted portions, the adjacent portions of said sills being slotted, a draft key extending through all of said slots 40 for supporting said yoke, a coupler pivoted to the forward continuation of said yoke for corresponding longitudinal movement therewith, and a backstop positioned between said sills adjacent the rear end of the yoke, and 45 formed to permit longitudinal movement of said yoke in both directions.

5. In a draft rigging, in combination with the center sills of a car, a horizontal yoke positioned between said sills and formed 50 with a rear U-shaped portion and forwardly extending arms, the forward ends of said arms being provided with slots, the adjacent portions of said sills being provided with slots registering with said yoke slots, a draft 55 key extending through all of said slots for supporting said yoke, the forward ends of the yoke arms being integrally united and formed with a pocket, a coupler associated with said yoke and provided with a butt portion extending into said pocket and an upright pivot pin extending through the walls of said pocket and said butt portion for connecting said coupler and yoke while allowing pivotal motion therebetween.

6. In a draft rigging, in combination with

the center sills of a car, a horizontal yoke positioned between said sills and formed with a rear U-shaped portion and forwardly extending arms, the forward ends of said arms being slotted, the registering portions 70 of said sills being likewise slotted and provided with reinforcing cheek plates connected adjacent said slotted portions and provided with corresponding slots therein, a draft key extending through all of said slots 75 for supporting said yoke, a front follower mounted on said key between the arms of said yoke, a rear follower mounted on said yoke adjacent the U-shaped portion thereof, a backstop positioned between said sills adjacent said U-shaped portion of the yoke, said backstop being formed with a forwardly opening pocket receiving said U-shaped portion of the yoke and upright abutments 80 engaging the rear follower for receiving buffing forces therefrom while permitting relatively free longitudinal motion of the yoke.

7. In a railway draft rigging, in combination with a coupler, a horizontal yoke formed with spaced forwardly extending flanges, means pivotally connecting said coupler and yoke intersecting the flanges of the yoke and a corresponding interspaced portion of the coupler and serving for the transmission of draft forces therebetween 90 and complementary curved bearing portions on the coupler and on the yoke serving to transmit buffing forces and permit relative pivotal motion therebetween.

8. In a railway draft rigging provided with cushioning mechanism and a coupler, a horizontal yoke, means pivotally connecting said coupler and yoke, an integral bridge portion on said yoke at the forward end thereof and formed for engagement with the 105 cushioning mechanism and provided with cylindrical bearing portions coaxial with the pivotal means and serving to receive the buffing forces from the coupler.

9. In a railway draft rigging, in combination with a coupler, a horizontal yoke, interspaced flanges on the adjoining ends of said members, a pin connecting said coupler and yoke and intersecting said interspaced flanges, the flanges on one being closely engaged by the flanges on the other and curved bearing portions, coaxial with the pin, provided on each member for pivotal engagement with the adjacent complementary flanges on the other member.

10. In a railway draft rigging, in combination with a coupler, a horizontal yoke, a plurality of rearwardly extending spaced flanges on the coupler stem, a plurality of forwardly extending spaced flanges on the yoke intermeshing with and closely embracing the flanges on the coupler, the outer edges of said flanges being curved coaxially, cooperating coaxially curved portions on each member engaging the curved outer 120 outer edges of the flanges on the other member.

edges of the flanges on the other, and a pin intersecting all of said flanges and coaxially arranged with respect to the curved portions thereon.

5. 11. In a draft rigging, a horizontal yoke, a coupler pivotally connected thereto, said coupler and yoke being movable together rearwardly upon the application of buffing forces to the coupler and a backstop co-
10 operating with the rear portion of said yoke to permit such movement.

12. In a draft rigging, in combination with the center sills of a car, a horizontal yoke positioned between said sills, a coupler 15 pivotally connected to said yoke and both movable rearwardly together upon the application of buffing forces, cushioning mechanism embraced by said yoke and a backstop receiving and supporting the rear end 20 of said yoke, while permitting such movement, and provided with abutments for receiving buffing forces from the cushioning mechanism.

13. A yoke of the horizontal type formed with an integral bridge portion connecting the forward ends thereof, adapted for engagement with cushioning mechanism and formed with forwardly extending spaced parallel flanges provided with coaxial cylindrical bearing portions, and coaxial cylindrical bearing pockets therebetween for pivotal engagement with cooperating portions on an associated coupler.

14. A yoke of the horizontal type formed with an integral diaphragm connecting forwardly extending arms thereof, adapted for engagement with cushioning mechanism and formed with forwardly extending spaced parallel flanges provided with coaxial cylindrical portions, and coaxial cylindrical 30 pockets therebetween for pivotal engagement with cooperating portions on the coupler, the flanges being coaxially apertured for receiving a pivotal member.

In testimony whereof I affix my signature.
DONALD S. BARROWS.
